UNITED STATES PATENT OFFICE

CLARENCE E. BLAKELY, OF MAPLETON, IOWA

CURTAIN ROD

Application filed August 18, 1930. Serial No. 475,942.

My invention relates to curtain rods of the type covered by my Patent No. 1,686,141, issued October 2, 1928.

The object of the present invention is to improve upon this type of rod by providing a more efficient locking device.

A further object is to provide an arrangement for supporting an auxiliary rod in connection with the main curtain rod, the auxiliary rod being mounted so as to be detachable from the main rod without disturbing the mounting of the main rod on a window casing.

A further object is to provide a detachable mounting of this kind including a bracket for connecting the auxiliary rod, the bracket also being detachable from the main rod when the main rod is unattached to a window casing.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Fig. 1 is a plan view of the rod support on the window casing.

Fig. 2 is a detail, sectional view through the rod and the locking device in inoperative position.

Fig. 3 is a similar view showing the device in locking position.

Fig. 4 is a plan view of the locking device.

Fig. 5 is a sectional view through the portion of the rod which attaches to a window casing and

Fig. 6 is a detail, sectional view taken on the line 6-6 of Fig. 1.

Fig. 7 is a detail, sectional view on the line 7-7 of Fig. 3.

Fig. 8 is a detail, enlarged, sectional view through the trigger.

I have used the reference character 10 to indicate generally a window casing of the type to which a curtain rod constructed according to my invention may be attached.

The rod comprises the main rod A and the

auxiliary rod B which have the telescoping rod sections 11, 12, 13 and 14, respectively.

The rod section 12 is intended to provide teeth 15 which are closely spaced according to the invention of my aforesaid patent. A locking device is carried by the rod section 11 and is adapted to engage the teeth 15. This locking device comprises a pawl member 16 which is made of spring metal and secured at 17 to the wall of the rod member 11 as by spot welding or the like.

The pawl 16 is provided with a hooked end 18 which is positioned to project through a slot 19 in the wall 11.

The member 20 is a trigger which is operated by the thumb nail of the operator and serves to hold the pawl in a retracted position as shown in Fig. 2. To this end the central portion 21 of the trigger is widened and flattened so that its width in a direction transverse to the plane of the trigger is considerably greater than its thickness.

It will now be seen that when the trigger is lying flat against the wall 11 as shown in Figs. 2 and 4 that the portion 21 thereof will be positioned with its greatest width between the pawl 16 and the wall 11 serving to hold the pawl in a retracted position.

When the trigger is lifted by inserting the thumb nail of the operator beneath it to the position shown in Fig. 3, it will allow the pawl to move toward the wall 11, the hook 18 extending through the opening 19 and engaging one of the teeth 15.

The advantage of this arrangement lies in the ease with which the device may be unlatched and in the complete concealment of the locking device within the curtain rod as illustrated in Fig. 7. When the operator wishes to remove a curtain rod, he inserts his finger between the flanges of the rod members 11 and 12 and runs it along the back of the rod until his finger touches the trigger 20. It is then an easy matter to crook the finger and lift the trigger 20 without actually seeing it.

When the curtain rod is being installed, the trigger is dropped to the position shown in Figs. 2 and 4 after the rods have been spread sufficiently to freely receive the window cas-

ing and the rods are then telescoped together against the casing as shown in Fig. 1, the inclined faces of the teeth 15 riding past the hook 18 and forcing it outwardly. The hook 16 will snap back into each depression between the teeth 15 as each tooth is passed and when enough pressure has been placed on the rod, the pawl will automatically lock the rod sections in engagement. In other words, the teeth 15 are saw-tooth shaped so that the pawl will ride over the teeth when the curtain rod sections are traveling into telescoping engagement but will lock to prevent the rod sections traveling out of telescoping engagement.

By providing the trigger in the form of a loop with the plane of the portion 21, at right angles to the plane of the loop, the trigger will lock itself in the position shown in Fig. 4. This occurs because the pressure of the lap 16 against the portion 21 opposes the initial raising of the trigger, the portion 21 having slightly passed dead center in reaching its Fig. 4 position.

25 The rods A and B include the end arms 22 and 23, respectively, the former being attached to jaw members 24 provided with teeth 25 to engage the casing.

30 The auxiliary curtain bracket 26 has the arm 27 to be received in the open end of the arm 22 and an arm 28 to be received in the open end of the arm 23. A finger 29 on the arm 28 extends through a slot 30 in the arm 23 and locks the rod B securely in engagement with the arm 26.

35 The advantage of this construction lies in the fact that the bracket 26 is held in place by the engagement with the casing 10 while the rod B may be removed from its brackets without disturbing the rod A.

40 Some changes may be made in the construction and arrangement of the parts of my invention without departing from the real spirit and purpose of my invention, and it 45 is my intention to cover by my claims any modified forms of structure or use of mechanical equivalents, which may be reasonably included within their scope.

45 I claim as my invention:

50 1. In a curtain rod, a pair of rod members, one of which telescopes within the other, a plurality of saw-tooth shaped teeth formed on one rod member, a pawl attached to the other rod member and provided with a free end terminating in a hook extending through said other rod member and positioned to engage one of said teeth and a trigger member having a portion of greater width than thickness interposed between the pawl and the adjacent wall of the rod member to which it is secured, said trigger member being capable of movement to rotate said interposed portion from a position wherein it holds the pawl out 55 of engagement with said teeth to a position

where it allows the pawl to ride against the teeth.

2. In a curtain rod, a pair of telescoping rod members, a plurality of teeth formed in the wall of one rod member, a pawl rigidly secured at one end to the other rod member and provided with a hook at its free end projecting through an opening in said other rod member, said hook being positioned to engage one of said teeth and the pawl being of spring material and mounted to normally urge said hook into said engagement and a trigger including a portion interposed between said pawl and a rod wall to which it is attached, said portion being of greater width and thickness and the trigger being movable to rotate said portion from a position wherein it holds the pawl in an inoperative position to a position where the pawl may engage said teeth.

3. In a curtain rod, a pair of telescoping rod members, a plurality of teeth formed in the wall of one rod member, a pawl rigidly secured at one end to the other rod member and provided with a hook at its free end projecting through an opening in said other rod member, said hook being positioned to engage one of said teeth and the pawl being of spring material and mounted to normally urge said hook into said engagement and means for holding the pawl out of engagement with said teeth, said means being movable to a position allowing the pawl to engage the teeth.

4. In a curtain rod, a pair of telescoping rod members, a plurality of teeth formed in the wall of one rod member, a pawl rigidly secured at one end to the other rod member and provided with a hook at its free end projecting through an opening in said other rod member, said hook being positioned to engage one of said teeth and the pawl being of spring material and mounted to normally urge said hook into said engagement and a loop shaped trigger including a portion of greater width and thickness interposed between the pawl and the wall to which it is secured, the remainder of the loop being positioned in a plane substantially perpendicular to the plane of said portion.

5. In a curtain rod, a pair of telescoping rod members, a plurality of saw-tooth shaped teeth formed in the wall of one of the rod members, a pawl rigidly secured at one end to the wall of the other rod member and provided at its free end with a hook projecting through an opening in said other rod member wall and adapted to engage one of said teeth, the pawl being of spring material and normally urging said hook into engagement with a tooth and a trigger including a portion of greater width and thickness interposed between the pawl and the wall to which it is attached, the trigger being adapted to be moved to rotate said portion from a position holding the hook away from the teeth to a

position where it does not interfere with the engagement of the hook with the teeth.

6. In a curtain rod, a pair of telescoping rod members, a plurality of teeth formed in one rod member, a pawl attached at one end to the other rod member and having a free end capable of movement toward and away from said teeth and adapted to engage one of said teeth and a trigger including a portion of greater width and thickness and interposed between said pawl and the wall to which it is attached, the trigger being adapted to be moved from a position where said portion holds the pawl away from contact with the teeth to a position where it does not interfere with the contact of the pawl with the teeth.

7. In a curtain rod, a pair of telescoping rod members, a plurality of teeth formed in one rod member, a pawl attached at one end to the other rod member and having a free end capable of movement toward and away from said teeth and adapted to engage one of said teeth and means to hold the pawl in an inoperative position, said means being movable to a position where it does not interfere with the engagement of the pawl with the teeth.

8. In a curtain rod, a pair of telescoping rod members, a plurality of saw-tooth shaped teeth formed in the wall of one rod member, pawl of spring material secured at one end to the wall of the other rod member and free at its other end to move from a position engaging said teeth to a position out of engagement with said teeth and a trigger including a portion of greater width and thickness interposed between the pawl and the wall to which it is secured, said trigger being movable from a position wherein the pawl engages one of said teeth to a position wherein the pawl is out of engagement with any of said teeth.

Signed this 16th day of August, 1930, in
45 the county of Woodbury and State of Iowa.
CLARENCE E. BLAKELY.
